UNITED STATES PATENT OFFICE.

CHARLES L. GEHNRICH, OF ELMHURST, NEW YORK.

SECTIONAL OVEN WALL.

Application filed May 16, 1927. Serial No. 191,777.

This invention relates to the method of constructing the walls and roof of that type of sectional oven which is especially suitable for baking japan or enamel upon metal articles.

The invention is designed to provide the oven with inner and outer panels arranged in parallel formation and staggered in relation to each other so that the heat from the interior of the oven cannot escape through the joints of the outer panel.

An object of the invention is to provide each panel with insulation such as a packing of asbestos to prevent loss of heat and the asbestos of an inner panel is adapted to face the asbestos of an outer panel thereby entirely covering the binding members whereby the panels are locked or keyed together.

The invention resides more particularly in the novel combinations hereinafter described and claimed, reference being made to the accompanying drawing in which:

Fig. 1 represents a horizontal section showing the side wall construction.

Fig. 2 is a vertical section of a roof construction.

Fig. 3 is a perspective view of a panel.

In the drawing is shown a metal panel having a back 5 provided with side rims 6 and end members 7 to form an open box like receptacle or compartment containing a non-heat conducting filling 8 such as asbestos. The rim has members 9 bent at right angles to the sides to prevent the asbestos from dropping out of the receptacle and to provide rigidity or support for the binding members 10 which lock the panels together. One panel is similar to the other and as indicated in Fig. 1 the vertical side and end walls of the oven are constructed by placing along side of each other in two rows one behind the other any number of the panels to form the inner and outer walls.

In this arrangement the panels are engaged by H shaped binding members 10 each co-acting with the side rim 6 of two panels placed side by side thus joining the panels together to obviate inner or outer movement. There can be any number of the panels connected together depending on the size of the oven. The panels of the sides and ends are joined together by means of corner sections 11 packed with asbestos 12 and having reduced portions 14 to fit the thickness of the inner and outer panel sections.

The outer panels are placed with the as-

bestos facing the asbestos of the inner panels and the panel as indicated in Fig. 1 is in staggered relation with the two panels behind it. The panels of one row substantially cover the panels of the other row and the parts of the binding connections where they contact with the rims of the panels are entirely covered by the asbestos. The two rows of panels provide a simple and efficient way of building the walls of a large oven and at the same time any of the sections can be removed for repairs or the oven can be entirely taken apart for transportation.

The roof section 15 as indicated in Fig. 2, consists of an inner and outer row of panels similar to the panels of the wall sections and one is longer than the other to provide stepped portions 16 to fit the end rims of the side walls. The panels carry a packing of asbestos 17 entirely covered by the plates of the panels when locked together. The corner joint is covered by means of a woven strip of asbestos 18 while an angle iron 19 superimposed on the asbestos prevents outward throw of the panels. When the panels are in place the metal seals the asbestos and dust or any other foreign matter cannot enter the compartment to mingle with the asbestos. Any number of the roof panels can be arranged side by side in staggered formation depending on the size of the oven. In order to keep the ends of the roof and side panels from being displaced or shifting inwardly angle irons 20 secured to the back of the panels can be employed.

I claim:

1. A sectional oven wall comprising a plurality of inner and outer panels one behind the other the meeting ends of the outer panels being covered by the panels behind them each panel having a packing of insulating material, and means relative to each pair of panels for locking them together.

2. A sectional oven wall comprising an inner and outer row of panels one behind the other the meeting ends of the outer panels being covered by the panels behind them each panel having a packing of insulating material, and means relative to each pair of panels in a row for locking them together.

3. A sectional oven wall comprising an inner and outer row of panels one behind the other each panel having a packing of insulating material the meeting ends of the outer panels being covered by the panels behind

them, and binding members coacting with each pair of panels in a row for connecting them together.

4. A sectional oven wall comprising an inner and outer row of panels one behind the other each panel having a packing of insulating material the packing of one row facing the packing of the other row the meeting ends of the outer panels being covered by the panels behind them, and binding members coacting with each pair of panels in a row for connecting them together.

5. A sectional oven wall comprising an inner and outer row of panels one behind the other each panel having a packing of insulating material the packing of one row facing the packing of the other row the inner panels being arranged in staggered formation relative to the outer panels thereby cov-

ering the joints of the inner panels, and binding members coacting with each pair of panels along side of each other in a row for connecting them together.

6. A wall unit suitable for a sectional oven, comprising a panel having a back provided with a rim forming an uncovered receptacle, and a non-heat conducting insulating material contained in the receptacle.

7. A wall unit suitable for a sectional oven, comprising a panel having a back with side rims each rim including a member disposed at an angle thereto and end members forming an uncovered receptacle, and a non-heat conducting insulating material contained in the receptacle.

In testimony whereof I have hereunto set my hand.

CHARLES L. GEHNRICH.
